UNITED STATES PATENT OFFICE.

KATHERINE L. DRUMMOND, OF CHICAGO, ILLINOIS, ASSIGNOR TO T. BUETTNER & CO., INC., OF CHICAGO, ILLINOIS, A CORPORATION OF ILLINOIS.

DESIGN FOR A LAUNDRY BAG.

Application filed March 27, 1926. Serial No. 17,082. Term of patent 3½ years.

To all whom it may concern:

Be it known that I, KATHERINE L. DRUMMOND, a citizen of the United States, residing at Chicago, county of Cook, and State of Illinois, have invented a new, original, and ornamental Design for Laundry Bags, of which the following is a specification, reference being made to the accompanying drawing, forming part hereof.

The figure is a plan view of a laundry bag, showing my new design.

I claim:

The ornamental design for a laundry bag as shown.

KATHERINE L. DRUMMOND.
